BALL AND PIN HANDLING MECHANISM FOR
BOWLING PIN SETTING MACHINES

Gottfried J. Schmidt, Pearl River, N. Y., assignor,
by mesne assignments, to Bowling Patents
Management Corporation, New York, N. Y., a
corporation of New York

Application January 1, 1942, Serial No. 425,318

20 Claims. (Cl. 273—43)

This invention relates to a bowling pin setting machine and more particularly to improvements in mechanism for returning the ball to the player after a ball has been thrown in order that the play of the game may continue as rapidly as possible.

While machines have been designed in which bowling pins and balls have been removed from the pit of a bowling alley following the throwing of a ball at pins standing on the bed of an alley, there has always been difficulty in returning the ball to the player with sufficient rapidity to insure that the game will not lag or be unduly lengthened because of the relative slowness of the mechanism employed in returning the ball to the player. It is an object, therefore, of this invention to provide a machine in which an improved ball return mechanism is operative in returning the ball to the player in a minimum of time after its arrival in the alley pit.

While my invention is readily adaptable for use with any type of machine employing ball lifting mechanism, it relates more especially to a bowling pin setting machine having pin and ball handling devices of the kind shown in co-pending application, Serial No. 323,062, filed March 9, 1940 by Gustaf E. Hagquist for Pit elevator for bowling pin setting machines. I have found that a more efficient and rapid ball return can be effected and have modified the mechanism shown in that application by introducing a separate and positively actuated ball handling device which normally is active in removing the ball from the pit of the alley in advance of the movement of the pin elevator which is responsible for removal of the pins from the pit and their distribution to suitable pin arranging mechanism (not shown).

It is an object of this invention to provide a bowling pin setting machine having independently operated mechanisms for conveying fallen pins and bowling balls from the pit portion of an alley to distributing devices which distribute them for the continued playing of the game.

It is a further object of my invention to provide novel pin and ball handling devices operative to remove both pins and balls from the pit of a bowling alley, but one wherein the device which handles the ball is actuated first to lift the ball from the pit and separate it from any pins which tend to associate themselves with the ball, after which the pin removing device removes pins from the pit, whereupon both devices are returned to their inoperative positions in the pit of the alley ready for handling more pins and balls as the play of the game proceeds.

It is also an object of my invention to provide a ball lifting device which may consist of spaced ball supporting elements extending transversely across the pit of a bowling alley, which device is arranged to move vertically with a ball supported on the cross members, and is operated at a given time to move and discharge the raised ball therefrom onto a ball return runway.

My invention also consists in the provision of 10 separate ball and pin handling mechanisms for removing balls and pins from the pit of a bowling alley, and means operative upon arrival of a ball in the pit for causing the ball removing mechanism to remove the ball from the pit in advance of the operation of the pin handling mechanism.

My invention is further characterized by the provision of a ball lifting device operative to separate fallen pins lying in the pit of a bowling 20 alley from a ball which is normally directed onto the ball lifting device in order that it may be raised and ejected by the ball lifting device at the appropriate time.

My invention is further characterized by a ball 25 lifting device movable into and out of a pit of a bowling alley which normally remains in the pit until a ball has positioned itself thereon, either by gravity or positively actuated means. The invention also consists in the provision of suitable 30 cooperating mechanism so that as the ball lifting device is raised its movements will be controlled properly for ejecting the ball therefrom, and be maintained in an elevated position spaced from the pin lifting device which operates subsequent 35 to the lifting of the ball to convey pins from the pit for distribution and resetting.

My invention is further characterized by relatively 40 movable pin and ball handling members positioned in the pit of a bowling alley and means for raising these members separately at different portions of the machine cycle to convey balls and pins from the pit of the alley and means for controlling the movement of these members into and out of the pit.

My invention is also characterized by the provision 45 of mechanism operative solely for the purpose of removing balls from the pit of a bowling alley and coacting mechanism which insures the removal of a ball from the pit if for any reason the first-named mechanism has not removed the ball.

With these and other objects not specifically mentioned in view, the invention consists in certain combinations and constructions which will

be hereinafter fully described, and then set forth in the claims hereunto appended.

In the accompanying drawings which form a part of this specification, and in which like characters of reference indicate the same or like parts:

Figure 1 is a side elevation of the pit end of an automatic bowling machine, showing the arrangement of the improved pit, ball and pin elevator mechanism;

Figure 2 is an end elevation of the same, from line 2-2 of Figure 1;

Figure 3 is a partial detail view of the ball lift;

Figure 4 is a top plan view of Figure 1; and

Figure 5 is a partial sectional view on line 5-5 of Figure 4.

Referring to Figures 1 and 2, the improved ball and pin handling devices are supported by vertical channel beams 10 suitably attached to the side walls 11 of the pit. The pins P are set up in any desired playing arrangement at the end of an alley 12 over which a member 13 is adapted to sweep in order to clear the alley of fallen pins after a ball B has been thrown or to remove unwanted standing pins and "deadwood" after throwing of the last ball allotted for each frame. The sweeping mechanism may be similar to that shown in Rundell patent, No. 2,250,503 granted July 29, 1941. The pins swept from the alley into the pit fall upon an apron 39 which extends over a movable platform or table 14. The thrown ball, after striking a bumper 15 mounted on a cross-bar 16 at the rear of table 14, comes to rest upon apron 39. The table 14 is covered by a suitable mat 17, such as rubber, which not only protects the balls and pins from damage, but also deadens the noise of impact. In the preferred embodiment, table 14 is provided with side beams 18 by which its rear end is hinged by bolts 19 carried by plates 20 suitably mounted on the floor of the pit. Near its forward end, the under-side of table 14 carries a metal plate 22 to which is adjustably attached an adjustable stop 23 resting upon a spring 24 embedded in a support block 25. The plate 22 also carries two adjustable contacts 26 adapted to close a normally open switch 27 on block 25 when the table 14 is moved into switch closing position by a ball falling thereon.

Located adjacent the top and to the rear of the bumper 15 is a partition 28 having a lower curved portion 28a extending to a point adjacent bumper 15 in order to prevent possible jamming of pins during the operation of the apron 39. The partition 28 may be slightly inclined and with walls 32, forms a pin receiving chamber 29 for directing pins into a pin transfer chamber 30 between partitions 31 and 32 and the side walls 10 of the machine. A conveyor 33, located in the chamber carries pins P to the pin storage magazine (not shown) from whence they are transferred at desired periods by means (not shown) to the bed 12 of an alley. Near the top of partition 28 and the entrance to chamber 29 is placed an apron supporting device, such as a horizontal roller 34, mounted on a shaft 35 supported in suitable bearings formed in the side frames 10 of the machine and rotatable by a sprocket 36 fast thereto. This roller is provided with an angular slot 37 in which is secured, as by screws or bolts 38, one end of the pit apron 39. The apron is preferably made of any suitable flexible material or fabric, such as rubber, canvas or other cloth, or may be made up of a laminated fabric such as canvas and rubber. Since the material will be subjected to rigorous wear and tear because of the impact of balls and pins, it is essential that

it be strong and durable. As shown in Figure 2, the apron may be constructed of a single piece of material of alley width or, if desired, it may be built up of several sections sewed or otherwise secured together.

In Figure 1, the apron is shown in its pin and ball receiving position in which it extends downwardly from roller 34 in front of bumper 15 to and along mat 17 of the pit table 14 and near the rear end of the alley 12 is fastened to a cross member of bar 40 formed of wood or other suitable material. The apron 39 may be attached to the bar 40 in any desired manner but it has been found that screws 42 perform this function with considerable satisfaction. It will be seen, therefore, that the apron accommodates itself readily to the pit and provides a maximum amount of space available for the reception of bowling pins and balls.

The ends of cross-bar 40 are located for engagement and travel in channel guide rails 45 which are mounted preferably on the side walls 11 of and within the pit but which extend upwardly along the side of the machine as shown in Figures 2 and 4. For best results, the ends of bar 40 are provided with metal pieces secured thereto by screws, or if desired, cam rollers or other devices might be used. Bar 40 is suspended by cables 46 which run over guide pulleys 47 mounted on shafts 48 secured for rotation in the side frames 10 of the machine to sheaves 49 on a shaft 50 to which sheaves they are fastened by screws 51.

The shaft 50 is turned by a gear 52 meshing with a gear segment 53 fulcrumed on a shaft 54 and having a cam follower 55 in engagement with a track 56 of a cam 57 on cam shaft 58. The cam shaft 58 has a sprocket 59 driven through a chain 60 by a sprocket 61 on the main shaft 62 to which is affixed by a key 63 the driven member 64 of a one-revolution clutch, the driven member 65 of which runs loose on shaft 62 and is continuously driven by a chain 66 on a sprocket 67 fixed thereto by a key 68.

The clutch 64, 65 is held in disengagement by the armature 69 of a solenoid 70 connected to lever 69a which engages a lever 71 turning on a stud 72 and depresses a spring 73 in member 64 whenever the solenoid is not energized. But, when a current flows momentarily through this solenoid, its armature 69 is pulled up, releasing the lever 71 from engagement with lever 69a thereby allowing spring 73 to raise the same against a stop surface 74 of member 64, in which position one edge of a half round portion 75 of stud 72 engages with a groove 76 in member 65, thereby interlocking the members 64 and 65 and driving the sprocket 61. After cessation of the momentary current in solenoid 70, the armature 69 drops back into the full-line position so that, after one revolution of the clutch, the lever 71 slides back under bell crank 69 and depresses spring 73, thus disengaging the clutch. The driving clutch and control mechanism may be of the same general construction as that shown and described in the above referred to Rundell patent.

While the clutch is in engagement, a sprocket 77 on shaft 62, through a chain 78 and a sprocket 79 on shaft 80, drives a gear 81 meshing with a gear 82 on a shaft 83 having a sprocket 84, which through a chain 85, drives the sprocket 36 on roller shaft 35.

Figures 1, 2, 3 and 5 show my novel ball handling mechanism which is independently movable into and out of the pit. This mechanism in the preferred embodiment consists of a frame

or cradle designated generally 98 extending transversely across the pit of the alley and comprising end support bars 100, 102, one of which bars 100 is provided with an angular arm 104 mounting a cam follower or roller 106 adapted for a purpose described hereinafter. Bars 100, 102 at their ends mount transverse rods, or rollers 114, 116 which preferably are so spaced that they support a bowling ball to be lifted thereby on a great circle X (Figure 1) having a radius less than the radius of a ball, which means that the ball to be lifted will rest high-up on the frame for ready ejection therefrom. Balls usually vary little in diameter and hence the frame functions equally well for all balls.

Since balls are quite expensive and rather easy to damage, in the form selected for illustration, rod 116 has a soft rubber covering, and hence balls upon arriving in the pit and on apron 39 and hitting this rod will be unaffected thereby. A similar covering can be used on rod 114 but usually this is unnecessary because it has been found advantageous for better handling of pins and balls in the pit to provide a transverse depression 118 in apron 39 by means of a U-shaped member 122 suitably secured to the underside of the apron in which rod 114 may lie when the lifter frame is stationed in the pit. As shown in Figure 1, rod 114 normally lies either below the surface of the apron or substantially tangent thereto. As mentioned above, rollers may be used instead of fixed bars, although the latter have been found very satisfactory.

As shown in Figures 1, 2 and 5, frame bars 100, 102 are provided with projecting pins or stub shafts 108 pivotally mounted in slides 110, 111 arranged to slide in substantially vertical guide tracks 124, 125 fixed to side walls or kick-backs 11, in any suitable manner. As shown, guide tracks 124, 125 are secured in slots 123 cut on the inside faces of the kickbacks 11 and extend upward beyond the limits of the kickbacks, and along the outside of the vertical frames 10 (Figures 2 and 4) in order to dispose slides 110, 111 and their actuating cables 112 in best operative positions relative to their operating mechanism, described in detail hereinafter.

Referring to Figure 1, it will be seen that guide 124 is formed with two cam portions 126, 128, whereas guide 125 is formed as a straight channel member in which slide 111 travels. It will be evident, therefore, that as slides 110, 111 are raised in their respective guides to lift the frame 98 with a ball held thereon, cam follower 106 on arm 104 will follow the track of guide 110 until it reaches branch 127 of cam portion 126 formed by a wall of guide 125 and a block 129 at which time frame 98 swings from ball supporting position II to ball ejecting position III and discharges the ball upon a ball return 92 which may consist of two spaced inclined rods or bars 90, 91 extending transversely across the machine adjacent roller 34 for discharge of the ball through one of the side frames to a conventional ball return 93. A spring 133 fixed to the upper end of block 129 yields to allow cam follower 106 to pass out of branch 127 into guide track 125 during the upward travel of cradle 98 and constrains follower 106 to move only in track 125 as the cradle is lowered into the pit.

Pivotaly mounted at 132 on the side frames of the machine are frame tilt levers 130. These levers, which are provided with pins 134 tracking in slots 136, are arranged to be engaged by bars 100, 102 as frame 98 approaches position III.

This coaction causes the frame 98 to swing about its pivots 108 in slides 110, 111 in the manner described above. Springs 138 fixed at one end to the levers 130 normally hold the levers in the position shown in Figure 1; when frame 98 is lowered levers 130 swing downwardly on their respective pivots against the tension of springs 138. Although two tilt levers have been shown, if desired one may be eliminated.

After frame 98 has been swung to position III, it continues to rise to its upper limits or position IV where it dwells until apron 39 carries out its designed functions of lifting pins from the pit. It will be noted (Figure 1) that apron 39 as it lifts pins is rolled upon roller 34 so that at its upper limits it assumes the dotted line position 39' inclined at an angle towards chamber 29 so that any and all pins carried thereby are discharged by gravity thereinto between bars 90, 91. If, for any reason, a ball is not lifted by frame 98, it will be transported by the apron 39 along with the pins lying in the pit, and when the latter are dumped into chamber 29, the ball will be separated therefrom by bars 90, 91 for return to the player. At position IV, frame 98 is held against a pin 145 in a position substantially parallel to apron 39 by means of a spring 139 suitably fixed to the side frame at 141. This arrangement insures against possible jamming or clogging of pins between the apron and ball lift frame.

The ball lift frame 98 is raised at the proper time by means of two sheaves 140 fixed to shaft 143 and preferably mounted outside the side frames 10. Cables 112 which extend upwardly from slides 110, 111 in guides 124, 125 are fastened to the sheaves so that when the latter are rotated slides 110, 111 and frame 98 attached thereto will be raised or lowered. Sheaves 140 are rotated by means of a rack 144 held in meshing engagement with a gear 142 on shaft 143 by means of a guide 146. Rack 144 is connected to a lever 148 fulcrumed on shaft 54, which lever is provided on its free end with a cam follower 150 tracking a cam 152 on shaft 58. Therefore, whenever a ball lands in the pit on platform 14 and shaft 58 is rotated, sheaves 140 will be rotated to raise the frame 98 and remove the ball from the pit. Cams 150 and 57 are so designed that frame 98 always moves in advance of apron 39 and effects the delivery of a ball prior to the removal of pins from the pit.

In general the angular inclination of the platform with respect to the transverse bars of the ball resting cradle is such that the ball positions itself by gravity between the two bars. That is, the ball lift cradle 98 is arranged to be located in the pit in any desired manner. However, as shown in Figures 1, 2 and 5, it is preferred to locate the cradle so that rubber covered bar 116 rests adjacent the base of the bumper (Figure 1) with the frame inclined downwardly with bar 114 positioned in transverse groove 118. In this position follower 106 lies in track 123 of guide 124. Because of this arrangement balls falling into pit P tend to roll towards the bumper, and locate themselves upon the cross bars 114, 116 of the cradle which results in the most efficient operation of the ball lift.

Occasionally pins are lodged on or between the transverse bars of the cradle, either alongside or in front or adjacent the bar so that there will be a tendency of the pins to push the ball out of proper located position on the cross bars. If there is a tendency for the pins to dislodge the

ball from its position on the rods, the action of the cradle in moving vertically upward is such that this tendency is overcome with the net result that the pins in most instances will be removed and the balls properly located thereon. The design of side guides 124, 125 is such, therefore, that the ball lifting frame or cradle 98 travels so that for the first fifteen or twenty degrees of movement in each cycle or as it begins to move upward because of the relative movement of follower 106 in guide portion 123, the rear bars are swung upward relative to the front or rubber coated bar, such that the ball will be back onto supported position on the two rods or, in effect, pushed towards the portion of the apron adjacent the bumper. This movement also has the effect of displacing pins which are lying on or adjacent the cradle so that they remain behind on the apron while the cradle lifts the ball.

In order to overcome any other tendency of balls to remain on the cradle or be lifted therewith along with the ball, means are provided for tilting the cradle at such an inclination, due to the co-action between cam follower 106 and guide 125, so that such pins are spilled off the cradle back into the apron in the pit (see position II, Figure 1). A satisfactory inclination of the cradle is 25 to 30° with the horizontal rubber coated or forward bar resting about the lower bar. Obviously any desired inclination can be used. Because of the fact that cradle 98 is inclined downwardly towards pit platform 14 during a part of its upward movement, it is maintained clear of the apron and so wear on that member is reduced. Also, because of this arrangement balls being lifted are held away from the vertical portion of the apron and at the same time any pins which might be lifted on the frame tend to drop therefrom back into the pit.

The invention above described may be varied in construction within the scope of the claims, for the particular device, selected to illustrate the invention, is but one of many possible concrete embodiments of the same. It is not, therefore, to be restricted to the precise details of the structure shown and described.

What is claimed is:

1. A ball and pin elevator for a pin setting machine for use with an alley having a pit at one end thereof comprising, a pin receiving and lifting member extending transversely across said pit, a ball supporting and lifting frame positioned on said member, and means for imparting separate movements to said frame and member to raise balls and pins from said pit.

2. A ball and pin conveying mechanism for use in a bowling alley pit comprising, a pin and ball receiving support located in said pit, a separate ball supporting and lifting cradle extending transversely across said pit above said support, and mechanism for imparting successive movements to said cradle and support to lift said ball and pins from said pit by separate movements.

3. A ball and pin conveying mechanism for use in a bowling alley pit comprising, a pin and ball receiving support located in said pit, a separate ball supporting and lifting cradle extending transversely across said pit above said support, mechanism for imparting successive movements to said cradle and support to lift said ball and pins from said pit by separate movements, and means operative upon arrival of a ball in said pit for setting said last-named mechanism into operation.

4. A ball handling device for use in removing

bowling balls from the pit of a bowling alley having a bumper at the rear of said pit, a ball supporting and lifting frame located in front of said bumper and movable into and out of said pit, means for raising said frame in front of said bumper with a ball thereon to separate said ball from pins lying in said pit and deliver said ball to a discharge station above said bumper, means operative at said station for ejecting said ball from said frame, and mechanism operative subsequent to the removal of a ball by said frame for lifting said pins from said pit in front of said bumper and discharging the same at said station.

5. A ball lifting device for use in removing a ball from pins in a bowling alley pit comprising, a single frame member provided with a plurality of spaced ball supporting bars extending transversely across said pit, means mounting said frame member for substantially vertical movement into and out of said pit, means for imparting a plurality of motions to said frame member during its movement with a ball supported on said bars to a ball discharge station, means for tilting said frame member at said station to discharge said ball from said frame member, and mechanism for moving said frame member cyclically into and out of said pit.

6. In a ball and pin handling mechanism for use in removing bowling balls and pins from the pit of a bowling alley having a bumper at the rear of said pit, an inclined pit platform, a flexible apron having a portion thereof extending vertically in front of said bumper, downwardly and across said platform, a transverse aperture formed in said platform, a transverse groove forming member attached to said apron adapted to rest in said aperture when said apron is in pin and ball receiving position, a ball lift cradle having spaced transversely extending ball supports movable into and out of said pit, and means for locating said cradle in said pit with one of said supports resting in said groove, and means operative upon arrival of a ball in said pit for imparting separate movements to said cradle and said apron for removing balls and pins by separate action from said pit.

7. In a ball and pin handling mechanism for use in the pit of a bowling alley having a bumper at the rear of said pit, a pit platform provided with a transverse slot inclined downwardly towards said bumper, a flexible apron having a portion thereof extending vertically in front of said bumper and downwardly across said platform, a ball lift cradle having spaced transversely extending ball supports, and side members mounting said supports movable into and out of said pit, and means for locating said cradle on said apron in said pit with one of said supports in said slot and with said side members inclined upwardly towards said bumper for receiving a ball rolling into said pit for separation from pins also lying therein.

8. In a ball and pin handling mechanism for use in the pit of a bowling alley having a bumper at the rear of said pit, a pit platform provided with a transverse slot inclined downwardly towards said bumper, a flexible apron having a portion thereof extending vertically in front of said bumper and downwardly across said platform, a ball lift cradle having spaced transversely extending ball supports, and side members mounting said supports movable into and out of said pit, means for locating said cradle on said apron in said pit with one of said supports in said slot and

with said side members inclined upwardly towards said bumper for receiving a ball rolling into said pit for separation from pins also lying therein, means operative upon the arrival of a ball in said pit for imparting separate operation to said cradle and apron, means for holding said cradle inclined during its movement to a point of ball discharge, means for moving said cradle to discharge a ball therefrom, and means for maintaining said cradle spaced from said apron during the operation of the latter.

9. A ball and pin conveying mechanism for use in a bowling alley pit comprising, a pin and ball receiving apron movable into and out of said pit, a separate ball supporting and lifting cradle also movable into and out of said pit extending transversely across said pit, means for positioning said cradle in ball receiving position above and adjacent said apron in said pit, mechanism operative in response to the arrival of a ball in said pit for effecting movement of said cradle with said ball supported thereon from said pit to a point of discharge, and other mechanism operative subsequently to the movement of said cradle from said pit to effect the movement of said apron and pins held thereon to a point of discharge, said apron also being constructed and arranged to lift said ball for discharge therefrom whenever a ball fails to be lifted by said cradle.

10. Ball and pin-pit elevating mechanism for use in a bowling pin setting machine comprising a ball elevator for removing a ball from the pit of a bowling alley to a point of discharge, a pin lifting elevator used for raising pins from said pit to a point of pin discharge, means operative at said ball point of discharge for rocking said ball elevator to discharge balls carried thereby, means for lifting said ball elevator an additional amount following the discharge of a ball therefrom, and means for moving said pin elevator to a point of discharge beneath said lifted ball elevator for discharge of pins therefrom free of engagement with said ball elevator.

11. Ball and pin-pit elevating mechanism for use in a bowling pin setting machine comprising a ball elevator for removing a ball from the pit of a bowling alley, a pin lifting elevator used for raising pins from said pit to a point of pin discharge, means operative at said point of discharge for rocking said ball elevator to discharge balls carried thereby, means for lifting said ball elevator an additional amount following the discharge of a ball therefrom, means for moving said pin elevator to a point of discharge beneath said lifted ball elevator for discharge of pins therefrom free of engagement with said ball elevator, and means operative after the discharge of balls and pins from their respective elevators for returning said elevators to said pit.

12. A ball elevator for a bowling pin setting machine for use with an alley having a pit at one end thereof, said machine having spaced vertical guide tracks adjacent the sides of said pit, comprising a frame extending transversely across said pit, ball supporting members mounted on said frame, said members being constructed and arranged to support a bowling ball and allow any pins tending to be raised therewith to drop from said members back into said pit, means on said frame tracking said guide tracks, a ball guide support in said pit, mechanism for raising and lowering said frame to lift balls from said pit, means forming a part of said guide tracks for coacting with said guides on said frame for swinging said frame to eject a ball carried thereby from said

frame when said frame is raised to a point of discharge, said guide tracks also including means for guiding said frame substantially vertically downward following the ejection of the ball therefrom for relocation in ball receiving position relative to said support in said pit, a cam portion formed on one of said guide tracks adjacent said pit, and means on said frame coacting with said cam portion for positioning said frame in ball receiving position on said support in said pit for delivery of balls onto said frame.

13. In a ball and pin handling mechanism for use in removing bowling balls from the pit of a bowling alley having a bumper at the rear of said pit, an inclined pit platform, a transverse aperture formed in said platform, a ball lift cradle having spaced transversely extending ball supports movable into and out of said pit, and means for locating said cradle in said pit with one of said supports resting in said aperture, and means operative upon arrival of a ball in said pit for imparting movement to said cradle for removing balls from said pit.

14. In a ball handling device for use in separating balls from pins in the pit of a bowling alley having a bumper at the rear of said pit, and removing said balls from said pit, a ball lift cradle including spaced ball supports, said supports being constructed and arranged to hold a ball being removed from said pit and allow pins to fall therebetween back into said pit, a platform in said pit, mechanism for moving said cradle in said pit, said mechanism including means for locating said cradle on said platform and maintaining said cradle in ball receiving position relative thereto, whereby a ball may be guided by said platform onto said supports, and means operative upon arrival of a ball in said pit for operating said mechanism to cause said cradle to move with a ball out of said pit while any pins in said pit remain therein.

15. In a ball and pin handling device for use in removing bowling balls from the pit of a bowling alley having a bumper at the rear of said pit, a pit platform, means positioning said platform inclined downwardly from a point adjacent the end of said alley towards said bumper, a ball lift cradle having spaced ball support members, mechanism for moving said cradle into and out of said pit and to and from a point of discharge, means for locating said cradle in said pit with one end on said platform and the other end inclined upwardly to a point adjacent said bumper, the relative inclinations of said platform and cradle constituting means for guiding balls onto said cradle, and means for operating said mechanism to cause said cradle to move a ball from said pit to said point of discharge.

16. A pit ball elevator for a bowling pin setting machine comprising, a cradle extending transversely across and movable into and out of a pit of a bowling alley, said cradle including spaced ball supporting members spaced apart a distance less than the diameter of a ball and greater than the diameter of a pin, an inclined ball delivery support in said pit, mechanism for locating said cradle on said support in said pit and maintaining said cradle stationary relative thereto prior to the throwing of a ball in position to receive a ball guided thereon by said support, said mechanism including means for raising said cradle to separate said ball from pins lying in said pit and convey said ball separately away from said pins in said pit to a point of discharge, means operative at said point of discharge for removing

said ball from said cradle, and means also forming a part of said mechanism operative cyclically for returning said cradle to said ball receiving position on said inclined support in said pit after said ball has been discharged therefrom.

17. A ball handling device for use in removing balls from the pit of a bowling alley having a bumper at the rear of said pit comprising, a single ball supporting frame movable into and out of said pit, an inclined pit platform, means for locating said frame in said pit with one end thereof resting on said platform, so arranged that a ball falling into said pit is guided by said platform onto said frame, mechanism actuated as a result of a ball arriving in said pit to effect the movement of said frame upwardly from said pit for separating said ball from pins in said pit and conveying said ball separately away from said pins in said pit to a point of discharge, and means operative at said point of discharge for swinging said frame to eject a ball therefrom, said mechanism also including means for returning said frame to said pit after a ball is discharged therefrom, and relocating said frame in ball receiving position relative to said platform.

18. A ball lift for use in separating balls from pins and removing balls from the pit having a bumper at the rear of said pit comprising, an elongated frame adapted to extend transversely of said pit and to be moved into and out of said pit, said frame including, end members adapted to be positioned adjacent the sides of said pit, spaced elongated ball supports carried by said frame and constructed and arranged to support a ball and allow pins in said pit and resting on said frame to drop therefrom back into said pit, a ball protective covering secured to one of said supports, an inclined pit platform, and means on said frame for locating said frame in said pit

with one end on said platform and the other end inclined upwardly towards said bumper, the relative inclinations of said platform and frame tending to insure delivery of balls onto said frame.

- 5 19. A ball pit elevator for raising balls from the pit of a bowling alley and separating said ball from any pins in said pit comprising a single frame member provided with two spaced bars extending transversely across said pit, an inclined pit platform, means for locating said frame in said pit and on said platform including, means for maintaining said frame stationary in ball receiving position relative thereto, said platform being constructed and arranged to guide balls onto said frame member, means for lifting said frame member to move said balls out of said pit to a discharge position, and means for rocking said frame member at said discharge position to discharge a ball therefrom.
- 10 20. A ball elevator for a bowling pin setting machine for use with an alley having a pit at one end thereof comprising, a frame extending transversely across said pit, ball supporting members on said frame, said members being spaced to support balls while pins tending to be elevated thereby fall by gravity back into said pit, an inclined ball guide in said pit, means locating said frame in said pit and on said guide in position to receive and support balls guided thereon by
- 15 25 30 35 said guide, mechanism for raising said frame out of said pit to a point of ball discharge and lowering and relocating said frame in position to receive balls directed thereto by said guide, means actuated in timed relation with the arrival of a ball in said pit and on said members to initiate the movement of said frame to said point of discharge, and means operative at said point of discharge for removing balls from said members.
